(57) CLAIM

I claim the ornamental design for a burp cloth, as shown and described.

DESCRIPTION

FIG. 1 is a perspective view of a burp cloth, showing my new design;

FIG. 2 is a top plan view thereof;

FIG. 3 is a front elevational view thereof;

FIG. 4 is a bottom plan view thereof;

FIG. 5 is a left-side elevational view thereof, the right-side elevational view being a mirror image thereof;

FIG. 6 is a rear elevational view thereof; and,

FIG. 7 is a cross-sectional view thereof, taken generally along lines 7-7 of FIG. 6.

The broken lines represent stitching, and are part of the claimed design.
